UNITED STATES PATENT OFFICE

2,537,445

ABRASIVE DISPENSER FOR STONE CUTTING SAWS

Joseph E. Couture, South Barre, Vt.

Application December 10, 1948, Serial No. 64,514

3 Claims. (Cl. 125—12)

1

This invention relates generally to stone cutting machines and more particularly to dispensing means for the abrasive used to accelerate the cutting action of the saws.

A primary object of this invention is to provide dispensing means for abrasive for use in connection with stone cutting saws, whereby the abrasive will be uniformly distributed to the different saw blades in a gang saw such as usually employed in these machines.

Another object of this invention, closely allied to the preceding object, is to accelerate the speed with which stones may be cut, the uniform distribution of abrasive to the different saw blades being reflected in increased cutting speed of the machine.

Still another object of this invention of a specific nature, is to provide a rotary hopper with means to charge solid abrasive into one end and means to allow overflow of solid abrasive mixed with a water carrier from the other end of the rotating hopper, the feed outlets being positioned intermediate the ends of the rotary hopper, and this construction permitting an assured ample charging of the hopper at all times during operation without the necessity of providing extremely accurate metering means.

Still another object of this invention, also of a specific nature, is to provide a rotary spout, which by virtue of its rotation and the general arrangement thereof with the other elements of the machine will not become clogged and will assure even distribution of the abrasive, the rotary spout being used in conjunction with a fixed-apertured distributor head and a plurality of adjustable distributor tubes leading from the distributor head to the different saw blades.

Yet another object of this invention is to provide improved means for returning used abrasive to the distributor means while bypassing the rotary hopper.

And a last object to be mentioned specifically is to provide dispenser means for abrasive for use with many different types of stone cutting saws, which will be inexpensive and practicable to manufacture, simple to use, and which will give generally efficient and durable service.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application, and in which:

Figure 1 is a side elevational view of the assembled machine;

2

Figure 2 is an end elevational view of the assembled machine, as viewed from the left hand side of Figure 1;

Figure 3 is an enlarged fragmentary detail view of vertical sectional character and taken substantially upon the line 3—3 of Figure 1;

Figure 4 is a horizontal sectional view taken on a line 4—4 of Figure 3, with the end of the rotary spout being removed; and,

10 Figure 5 is a three dimensional view of the part hereinafter referred to as the collector chute.

Similar characters of reference designate similar or identical elements and portions throughout the specification and throughout the different views in the drawings.

Referring now to the drawings in detail, this invention is adapted to be used with an environment including power drive means diagrammatically indicated at 10 and including a pitman 12 pivoted on a gang saw frame. The frame 14 is mounted by means of a plurality of links 16 on uprights 18 in the main frame of the machine, which main frame may be embedded in a concrete foundation 20. The foundation 20 may be provided with a pit 22 in which are mounted rails 24 to carry a trolley 26. The trolley 26 supports the stone 28 to be cut into slabs, and Figure 2 represents this stone as being partially cut and as having a plurality of saw kerfs 30 extending partially through the stone.

20 A pair of traveler blocks 32 are threadedly associated with vertically disposed and threaded rods 34 which are journaled in the vertical members 18 of the main frame of the machine and 25 which are provided with sprocket wheels at their top ends for coaction with an endless chain 36, so that the two rods will be rotated simultaneously by means of a pair of bevel gears 38 driven by a double pulley 40 and a belt 42, which belt will be understood to be operatively connected with suitable power means.

30 All the foregoing structure can be varied considerably from that described and illustrated herein, and the principal features of this invention are capable of incorporation and use with many different types of machines which may be considered as merely exemplified by the machine described above. The chief features of this invention may be considered as related to the rotary hopper generally indicated at 44, the collector chute 46, funnel 48 and rotary spout 50, together with the fixed distributor head 52, distributor tubes 54, each of which will be described in greater detail hereinafter. The invention also 35 includes a channel 56 leading from the pit 22 to a pump 58 and the pump returns abrasive and a water carrier therefor through a pipe 60 lead-

ing to the rotary hopper 44. Another pipe 62, with its branch pipes 63, is used to initially admit water directly to the collector chute 46, this pipe 62 having a control valve 65. The other main features of this invention include the tubular means 64 used for initially charging the rotary hopper 44 with solid granulated abrasive, and the overflow collector chute 66 at the opposite end of the rotary hopper, this last mentioned element 66 communicating with an overflow outlet in the rotary hopper, this overflow outlet being considered an important feature of this invention.

Referring now to certain details of construction, it may first be noted that the rotary hopper 44 is a hollow cylinder, inclined slightly to the horizontal and mounted for rotation about its longitudinal axis on a drive shaft 68 which is journaled in brackets 70 supported on the main frame of the machine and which is driven by a pulley 72 and a belt 74 connected to suitable power means, thought unnecessary to be illustrated in this application. One end of the hopper 44 is apertured as at 76 to receive the lower end of the tubular member 64 used to charge the rotary hopper with granulated solid abrasive, while the opposite end of the rotary hopper is apertured at 78 to provide what will be referred to as the overflow outlet for the hopper. Intermediate the ends of the hopper there are provided a plurality of feed outlets 80 which are circumferentially disposed on the hopper and aligned with the collector chute 46.

The rotary spout 50 is rigidly secured to the funnel 48 and to a drive pulley 82 which is represented as driven by a belt 84 connected to a source of power which is thought unnecessary to be illustrated. The funnel 48 receives abrasive and water from the collector chute 46 and the lower end of the rotary spout distributes this mixture to the distributor head 52 which may be constructed of two concentric vertical wall members 85 and 86 with radially disposed vertical walls 88 therebetween, and a plurality of short vertical outlet tubes 90 leading from a plurality of funnel-shaped floor panels 92, best shown in Figure 3. The inner vertical wall 86 may be further supported by a spider 93, and the distributor head 52 may be supported as a unit by a plurality of depending brackets 94 secured to suitable cross frame members 96 and 98 and angle members 100. The rotary spout is journaled in a bearing 102 carried by further cross members 104 which are supported by the frame members 96, and the drive pulley 82 may seat upon the upper end of the bearing 102. The tubes 54 are secured to the lower ends of the outlets 90 and these tubes may be flexible and adjustable so that the same may be shifted as desired to direct the abrasive to the different saw blades.

It will be noted that each of the collector chutes 46 and 66 are generally semi-circular in form and enclose lower portions of the rotary hopper 44. These chutes are rigidly secured by suitable brackets on the main frame of the machine, and the overflow outlet 78 communicates through the second collector chute 66, so that overflow abrasive and water will be directed into the pit 22 or into any suitable catch basin provided, according to the preferred method of operation as related to the particular conditions under which the machine is being used. In any event, the provision of the overflow outlet 78 assures that the rotary hopper can be maintained with a level of abrasive therein sufficient to make

certain that the abrasive will be dispensed uniformly from the rotary hopper, thereby assuring uniform operation of the machine.

The operation of this machine will be clearly understood from a consideration of the foregoing description of the mechanical details thereof, taken in connection with the drawings and with the above recited objects of the invention. Further description would, therefore, appear to be unnecessary.

Obviously minor variation from the details of construction of the disclosed embodiment may be resorted to without departure from the spirit and scope of this invention, and the invention should be determined as limited only by a proper interpretation of the terms used in the subjoined claims.

Having described the invention, what is claimed as new is:

20 1. An abrasive dispenser for a stone cutting saw, comprising a rotating hopper having feed outlets and an overflow outlet, distributor means to conduct abrasive from said feed outlets to the saw, means to return abrasive escaping from said overflow outlet to said hopper by-passing said distributor means, whereby abrasive moves through said hopper in greater volume than through said distributor means to assure ample and uniform supply to said distributor means, 25 said distributor means including a rotary spout mounted for rotation about a vertical axis and receiving abrasive from said feed outlets, and a plurality of adjustable tubes having their upper ends arranged in a circle to receive abrasive from 30 said rotary spout.

2. A dispenser according to claim 1 and including a collector chute partially surrounding said rotating hopper adjacent said feed outlets, and a funnel on the upper end of said rotary spout 40 to receive abrasive from said collector chute.

3. An abrasive dispenser for a stone cutting saw, comprising a rotating hopper having feed outlets and an overflow outlet, distributor means to conduct abrasive from said feed outlets to the saw, means to return abrasive escaping from said overflow outlet to said hopper by-passing said distributor means, whereby abrasive moves through said hopper in greater volume than through said distributor means to assure ample and uniform supply to said distributor means, a collector chute partially surrounding said rotating hopper adjacent said feed outlets, said distributor means including a rotary spout mounted for rotation above a vertical axis and receiving 45 abrasive from said feed outlets a funnel on the upper end of said rotary spout to receive abrasive from said collector chute, a water pipe leading directly into said collector chute from an outside source, and means to collect and to return used abrasive and water to said collector chute for re-use, said pipe and last mentioned means both by-passing said rotary hopper.

JOSEPH E. COUTURE.
